UNITED STATES PATENT OFFICE.

JOSEPH T. LANGLAIS, OF BERKELEY, CALIFORNIA.

TRAIN-STARTER.

SPECIFICATION forming part of Letters Patent No. 550,347, dated November 26, 1895.

Application filed January 29, 1895. Serial No. 536,575. (No model.)

To all whom it may concern:

Be it known that I, JOSEPH T. LANGLAIS, a citizen of the United States, residing at Berkeley, in the county of Alameda and State 5 of California, have invented certain new and useful Improvements in Train-Starters, of which the following is a specification.

This invention relates to an atmospheric train-starter; and its objects are, first, to produce a device that will effectively assist in starting a train of cars from the dead-stop, whether going forward or backward; second, to have a device of this class fully adapted to set and keep in motion the whole train of cars 15 unaided by the usual motive power if need be, as in the case when the driving engine or motor is disabled; third, to provide a starter for each car in a train, so that all the cars can be moved together; fourth, to devise a starting 20 apparatus that will be operative regardless of the way the cars are turned or the train is made up, and, fifth, to place the whole contrivance under the direct control of the engineer, motorman, or driver, as the case may be.

Referring to the accompanying drawings, 25 in three sheets, which form part of this specification, Figure 1 is a partly-broken side elevation showing how the starter is applied to each car. Fig. 2 is a top view of the construction shown at Fig. 1, some parts being removed. Fig. 3 is a cross-section on the line 30 *a a*, Fig. 2, looking toward the right. Fig. 4 is a cross-section on the line *y y*, Fig. 9, looking to the left. Fig. 5 is a sectional elevation, 35 on an enlarged scale, of an air-cylinder forming part of the starter. Fig. 6 is a top view of said cylinder. Fig. 7 is an end view of the same. Fig. 8 is a sectional elevation of an upper corner of the cylinder and parts connected therewith. Fig. 9 is a sectional plan 40 of the construction illustrated at Fig. 8 viewed from the top. Fig. 10 is a broken sectional elevation showing how the starter is applied to and acts upon the car-axles. Fig. 45 Fig. 11 is a cross-sectional elevation of the mechanism shown at Fig. 10. Fig. 12 is a broken plan of a brace that supports part of the starting apparatus from the axles. Fig. 13 is a similar view of a link or connecting-rod employed for working the mechanism connected 50 with the axles from the air-cylinder with which each car is provided. Fig. 14 is a sec-

tional side elevation representing the end of one of the air-pipes that are connected with the air-cylinders.

55

A represents the platform or bottom of a car, *B* the car-trucks, and *C* springs that are interposed between the trucks and car-bottom.

D and *D'* are air-pipes that are placed in parallel lines under the platform of each car in a train above the car-trucks. The pipes in each line are united between the cars by flexible rubber tubing, such as *E*, and suitable couplings, the pipes *D* and the tubes connected 60 therewith forming one continuous line throughout the entire train, while the pipes *D'* and their tubing form the connections between air-cylinders *F*, located one under each car at or near the middle. Both sets of pipes 65 and tubes run in straight lines, but the pipes *D'* are provided at their outer end with a branch pipe *D*², controlled by a ball-valve *d*, seated within a casing *d'*. This branch pipe is utilized to make connection between the 70 pipes *D* and *D'* at the rear end of the train, the flexible rubber tube attached to the last pipe *D* being then curved backward and secured to the end of said branch pipe instead of running out in the direction of the car, as 75 in the remainder of the train. The tube secured to the last pipe *D'* is also turned back and brought up to a plug *d*² when falling at the rear, in order to close the end of the line 80 of pipes to which it belongs.

85

The cylinders *F* are each provided with a piston *G*, whose normal position when at rest is in the center of the cylinder to which it appertains, the piston-rod *G'* passing through the head and projecting out of the cylinder 90 at both ends. Each end of the piston-rod is connected by one or more links or connecting-rods *G*² to a ratchet-lever *H*, passing over and adapted to swing about the reduced end of a sleeve *I*, fitted by preference around the axle 95 nearest to the cylinder at each end and in which said axle turns. By the side of the lever *H* is a ratchet-wheel *J*, which is rigidly secured to the axle in such a manner that the lever can work between it and the sleeve *I* 100 independently of either, the lever riding upon the smaller end of the sleeve and the ratchet-wheel turning by the side of it with the axle. The lever is provided with a drop-pawl *K*,

adapted to slide on it and slightly supported by a spiral spring k . This pawl is alternately thrown into and out of engagement with the teeth of the ratchet-wheel by a roller K' , working in connection with two curved guides L L' , located one on each side of and above the axle. These guides are carried by one of two cambers M , that are set in parallel lines between opposite timbers of the truck-frame, above which they are supported by upwardly-curved braces M' , rising from the sides of the sleeve I on opposite sides of the axle. The braces M' are arranged to pass through guides N , adapted to slide over them, so that the cambers and parts related thereto may not be affected by the occasional vertical movements of the truck-frame. The guides L L' are pointed at the ends, as shown in dotted lines at Fig. 10, upwardly at the inner ends and downwardly at the outer ends, in such a manner that if the lever H be moved from the center outward on either side the roller k' will be caught under the curved guides and the pawl engaged by the ratchet-wheel until the lever has been swung out as far as it will go, but if the lever be worked back from the sides to the center the roller will ride upon the guides and keep the pawl disengaged from the ratchet-wheel. The effect of this construction is that if the piston be moved forward from its normal position in the center of the cylinder the connecting-rod will pull the lever down in the same direction from its vertical position upon the axle, and the pawl and lever will turn the ratchet-wheel, as also the axle, forward. Driving the piston back to the center of the cylinder will push the lever back to its central position without affecting the axle and prepare it to give the axle another turn. Moving the piston to the back end of the cylinder will in like manner work the lever and pawl backward and turn the axle also backward. Bringing the piston from the rear end of the cylinder to the center again will swing back the lever and pawl independently of the axle, as in the other case, and put them in readiness for another move. One of the curved guides engaged by the pawl-roller is thus used for backing and the other for going ahead, the actual work of the lever and pawl being performed always from the center outward on either side.

The links or connecting-rods C^2 are secured to their respective levers by a double joint, as shown at Fig. 13, so they may work properly in rounding curves. They are also given the same curvature as the cambers M and located above them for the same reason—that is, in order that they may not interfere with the swiveling of the car-trucks beneath the cars, or break or twist, &c. The cambers and braces are connected, so as to work together in a vertical plane, passing through the side guides N and leaving the truck-frame free to move up and down. A small collar O , firmly fixed to the axle, is used to hold the sleeve I up to the ratchet-wheel.

The means employed for actuating the starter is atmospheric air, which is supplied from the locomotive or motor by any suitable agency—for example, an air-pump worked by steam. The only line of pipes used for conveying the compressed air to the cylinders when it is desired to move the train forward is that directly connected with the cylinders and composed of the pipes D' and connections, the air following the course indicated by the plain arrows, filling the pipes D' , the flexible tubes uniting them and the cylinders between them, and stopping at the rear end of the rear car in the train, where the last rubber tube turns up to the plug and the ball-valve closes the passage through the branch pipe. For moving the train backward, both the pipes D and D' are used, the air then following the course marked out by the double-headed arrows, flowing first through the pipes D and their connections for the full length of the train and coming to the cylinders from the rear end of the pipes D' , passing from one line of pipes to the other through the rubber tube attached to the branch pipe, where it dislodges the ball-valve and proceeds forward to the front end of the train. The pipes D' are therefore the only ones having direct communication with the air-cylinders, the pipes D being connected only to the air-pump at one end of the train and to but one branch pipe of the other line of pipes—that is, the one to be found at the rear end of the rear car.

The pipes D' are joined with the cylinders preferably by a screw-thread connection resting within air-chests P P' at each end of the cylinders and communicating with centrally-enlarged horizontal passages p p' , running through these chests. From the inner sides of the air-chests P P' run small pipes D^3 D^4 , which lead to a middle chest P^2 and establish communication between the passages p p' and similar but differently-located passages p^2 p^3 in the middle chest. The passages p^2 p^3 are crossed, as shown, and are independent of each other, having no intercommunication. At the lower ends of the crossed passages are pipe connections D^5 D^6 , leading back to the inner sides of the air-chests P P' , where they communicate with passages p^4 p^5 and through these with rotary valves Q Q' , that are seated on top of the cylinders at each end and revolve on central pivot-pins q q' , said valves reaching about half-way up the air-chests.

The rotary valves Q Q' have each a lateral passage q^2 q^3 running from their center outward and flaring outwardly to adapt it to register always with the adjacent passage p^4 p^5 within a certain range of oscillation. Besides this, each rotary valve has a vertical passage q^4 q^5 running, also, from their center to their upper end, where it is controlled by a check-valve R R' , another passage q^6 q^7 leading downwardly in an oblique direction from their center and adapted to communicate with

a port $f f'$ at each end of the cylinder on the upper side, and still another lateral passage $q^8 q^9$ running from their center to a corresponding passage p^6 , bored through the side 5 of each air-chest $P P'$ and communicating, through the medium of an outer passage or pipe $S S'$, with a lower port $f^2 f^3$ at the opposite end of the cylinder in the bottom side, each port $f^2 f^3$ being controlled by a clack-valve $f^4 f^5$. The rotary valves are swung on their axis to open or close the ports in the cylinder and to perform their other work or several other functions by means of a rod Q^3 , having a pin Q^8 , that enters a recess or notch Q^4 (see 15 Figs. 8 and 9) in the bottom of each valve. The cylinder has holes for the escape of air, or exhaust-ports $f^6 f^7$ at each end, on the upper side, two of which $f^6 f^7$ (one at each end) are controlled by the rods Q^2 , connected with 20 the rotary valves, and the others $f^8 f^9$ by similar rods Q^5 running parallel therewith, all these rods being fitted and arranged to slide in holes q^{10} bored through the heads and upper ends of the cylinder. The rods $Q^2 Q^5$ are 25 connected at their outer ends by a cross-head Q^6 , and have springs Q^7 coiled around them that keep them back and retracted almost to the full extent. The rods $Q^2 Q^5$ also have each two holes $q^{11} q^{12}$, adapted to alternately register with the exhaust-ports $f^6 f^7$ according 30 as the rods are driven into the cylinder or withdrawn from it. The rods are kept in the position illustrated, with the exhaust-ports closed, by means of an intermediate rod T loosely fitted within the cross-head Q^6 , on the 35 outer side of which it bears through the agency of a nut t and rigidly secured to a swinging piece T' , hinged at t' to the cylinder-head and adapted to be oscillated in a vertical plane by a horizontal bar T^2 , resting 40 normally on the top of a saddle T^3 , carried by a standard T^4 rising upwardly from the piston-rod, to which it is secured by a suitable collar T^5 . Upon the piston being driven forward or backward the standards and saddles move in the same direction together with their respective end of the piston-rod, and one of the bars T^2 slides over and past the saddle upon which it bears, while the opposite bar 45 is dropped from the saddle upon which it previously rested. The swinging piece attached to the dropping bar drops also and draws back with it the intermediate rod T , allowing the springs Q^7 to repel the cross-head Q^6 and retract the rods $Q^2 Q^5$ far enough for the holes 50 q^{11} to register with the exhaust-ports, the rod Q^2 at the same time acting upon the nearest rotary valve. A strap T^6 is provided to limit the outward movement of the swinging piece 55 and regulate the withdrawal of the rods. The piston being moved still farther—that is to say, proceeding on its course—the standard that slides by the side of the bar T^2 , which remains in a raised position, is carried by the piston-rod toward the cylinder, and having a bent finger or lateral projection t^4 at the top 60 is soon brought into contact with the cross- 65 head Q^6 nearest to it and pushes it toward the cylinder, thereby acting upon the rods $Q^2 Q^5$ connected to said cross-head, acting upon the nearest rotary valve and bringing the holes q^{12} to the exhaust-ports.

The starter operates as follows: If it is desired to go ahead and move the train forward, the compressed air is forced through the pipes 70 D' in the direction of the plain arrows in Figs. 1, 2, and 5. The air enters first the three air-chests before reaching the cylinder, passing through the passage p above the valve R' on to the pipe D^3 , the passage p^2 , the pipe D^5 , the passage p^4 , the passage q^2 , the passage q^6 , and the port f , when it fills that one-half of the cylinder back of the piston. A certain pressure having been reached there, the air forces its way up through the passage q^4 and 80 throws back the valve R , which closes that part of the passage p' communicating with the pipe D^4 , and opens communication with the other part of the passage p' that connects with the next section of pipe D' , thus allowing the 85 air to flow on through the next cylinder and from that one to all the others until the rear end of the train is reached and the air stops at the plug terminating the line of pipes D' . The pressure being maintained and increasing 90 gradually, the piston of each cylinder is then moved forward, thereby working the ratchet-levers and their connections and turning the car-axle with which each lever is connected. While the piston is moved forward, the standard and saddle carried by the front end of the piston-rod let drop the oscillating bar which they carried when at a standstill, and the swinging piece at the front end of the cylinder falling outward with its intermediate rod the springs Q^7 move out the rods $Q^2 Q^5$ far enough for the holes q^{11} to register with the exhaust-ports, and consequently afford exits for the escape of the air contained in that part of the cylinder lying 100 in front of the piston. This also turns the rotary valve at the front end so that no compressed air can enter it. As the piston completes its stroke, the rear end of the piston-rod brings up the standard, which it carries to 105 the rear end of the cylinder, where the finger on the standard is made to contact with the rear cross-head Q^6 , and consequently to drive in the rear rods $Q^2 Q^5$. This causes the holes q^{12} to register with the exhaust-ports at the 110 rear end of the cylinder and turns the rear rotary valve. In turning the valve communication is cut-off between the passage q^6 and the port f and established between the passages q^8 and p^6 and the pipe S , while on account of 115 the flaring mouth of the passage q^2 the air keeps coming through it. Having then the port f closed, the exhaust-ports at the same end of the cylinder open, and the current or flow of air diverted through the pipe S to the 120 opposite end of the cylinder, it follows that the cylinder is soon emptied of the compressed air previously forced in behind the piston, and the piston is driven back to where it 125 130

started from, when the valves and ports resume their normal positions and functions. The operation can then be repeated at will, either to assist the train in starting or to bring it to some desired place. To go backward, the operation is substantially similar except the air is brought in to the cylinders through the line of pipes D and from the rear end of the line D', the air lifting the ball-valve in the rearmost branch pipe and entering the cylinders by way of the passage p', pipe D⁴, passage p³, pipes D⁶, passages p⁵, q³, and q⁷, and the ports f', so as to strike the front end of the pistons and drive them backward, thereby working the ratchet-levers also backward and turning the axles in that direction.

What I claim, and desire to secure by Letters Patent of the United States, is—

1. A train-starter consisting of an air-cylinder having suitable entry and exhaust ports and suitably supported beneath each car in the train, a piston adapted to reciprocate therein, a supply of compressed air, pipes and corresponding conduits communicating with each cylinder and the air-supply whereby the air is conveyed to the same side of all the pistons to move them simultaneously in the same direction, piston-rods, ratchet mechanisms actuated by said piston-rods and adapted to rotate one or more axles of each car in either direction, valves controlling the passage of air through said pipes and conduits, and valve-shifting mechanisms operated by the piston-rods whereby the flow of air is diverted and brought to the opposite side of the pistons to drive them back to their normal position, substantially as set forth.

2. In a train-starter, the combination of an air-cylinder, an air-chest connected therewith, a piston normally resting in the center of said cylinder, valved conduits admitting compressed air into said air-chest and the cylinder and conveying the same first one side of said piston and then on the other, a piston-rod, and intermediate mechanism between the piston-rod and one or more car-axles whereby the latter are turned by the reciprocating movement of the piston, substantially as set forth.

5. 3. The combination of a car-axle, a ratchet mechanism adapted to rotate the same, an air-cylinder having suitable entry and exhaust ports, a piston reciprocating in said cylinder, a piston-rod adapted to operate said ratchet mechanism, an air-chest, valved conduits between said air-chest and the cylinder whereby air under pressure is applied to both sides of the piston alternately, a spring-retracted rod controlling the exhaust ports and the valved conduits, and means whereby said rod may be driven from the piston-rod, substantially as set forth.

4. The combination of the air-cylinder, the piston centrally located therein, the piston rod projecting from both ends of the cylinder, the air-chests and valves therein, the pipes

connected with the air-chests, the valved conduits conveying the compressed air from one chest to another and into the cylinder on opposite sides of the piston alternately, mechanism working in conjunction with each end of the piston-rod to shift the valves in the air-chests and conduits, and connections between the car-axles and the two ends of the piston-rod whereby the reciprocating movement of the piston within the cylinder operates to turn the car-axles, substantially as set forth.

5. The combination of a car-axle, a ratchet-wheel secured thereto, cambers supported from the axle by braces passing through slides on the truck-frame, guides on opposite sides of the axle carried by the cambers, a ratchet-lever, a spring-supported pawl on the ratchet-lever, a roller on the pawl alternately passing under and riding over the guides on the cambers, thereby throwing the pawl into and out of engagement with the ratchet-wheel, and actuating mechanism, substantially as set forth.

6. The combination, in a train-starter, of an air-cylinder located beneath each car in the train, a piston in each cylinder, a supply of compressed air, pipes connecting the series of cylinders at both ends with the air-supply, pipe connections between the cylinders, and valved conduits adapted to convey the air primarily to either side of the pistons whereby the air may be supplied both ways through the same pipe connections, substantially as set forth.

7. The combination, in a train-starter, of an air-cylinder provided with a piston and located beneath each car in the train, a supply of compressed air, pipes and suitable tubing connecting the cylinders with the air-supply, said pipes being each provided with a valved branch at the outer end, and a second line of pipe also communicating with the air-supply and adapted to be coupled with the valved branch of either of said branched pipes, substantially as set forth.

8. The combination of an air-cylinder having suitable entry and exhaust ports and provided with a reciprocating piston, a piston-rod, means for conveying compressed air to the cylinder to move the piston therein, a valve controlling the flow of air to both ends of the cylinder, shifting mechanism for said valve operated by the piston-rod whereby the air first applied to one side of the piston is automatically diverted and directed against the other side thereof, a car-axle, and connections between the axle and piston-rod whereby the axle is rotated by the reciprocation of the piston, substantially as set forth.

In testimony whereof I affix my signature in presence of two witnesses.
